UNITED STATES PATENT OFFICE.

WILLIAM CHARLES BRETT, OF LONDON, ENGLAND, ASSIGNOR TO BARNETT ABRAHAMS, OF SAME PLACE.

MACHINE FOR FILLING TUBES OR OTHER RECEPTACLES WITH RUBBER SOLUTION, &c.

SPECIFICATION forming part of Letters Patent No. 619,067, dated February 7, 1899.

Application filed July 6, 1897. Renewed July 9, 1898. Serial No. 685,534. (No model.)

To all whom it may concern:

Be it known that I, WILLIAM CHARLES BRETT, a subject of the Queen of Great Britain, residing at London, England, have invented new and useful Improvements in Machines for Filling Tubes or other Receptacles with Rubber Solution and other Substances, of which the following is a specification.

This invention relates to improvements in machines mainly adapted for filling tubes or other receptacles with solution for repairing punctures in tires, but which may also be used for filling tubes with paint, soap, printing-ink, and other substances. In such machines as now generally made the solution is forced into the tube to be filled through a nozzle from a cylinder by means of a piston actuated by a screw, and this construction of machine has the disadvantage that a considerable quantity of the solution escapes and also that loss of time is occasioned in refilling the machine with solution when the cylinder has become exhausted.

Now it is the object of this invention to obviate these disadvantages, and to this end I provide a reservoir for containing the solution, communicating with one end, preferably the rear end, of a cylinder, the piston of which is so constructed that the solution is drawn into the cylinder behind it during its forward stroke and can pass through it to the front of the same during its backward stroke in order that it may be forced through a nozzle on the front end of the cylinder when the piston moves forward for its next stroke. The nozzle, on which the tube to be filled is placed, is provided with a valve or cock designed to be operated by a series of levers and links or the like in connection with a piston-rod in such a manner that the said valve or cock is closed immediately the piston starts to move backward, so that as the tube is removed from the nozzle no solution is forced out by the pressure of the piston behind it, thus avoiding all waste.

In some cases I provide the valve or cock with a spring, whereby it is maintained normally closed and is opened by the movement of the handle for effecting the forward movement of the piston. By this means it will be

obvious that the valve or cock is closed immediately pressure is removed from the handle.

In the accompanying drawings, Figure 1 is a sectional elevation of a machine for filling tubes with rubber solution or other substances 55 constructed according to my invention. Fig. 2 is a sectional plan of the machine; and Fig. 3 is a section on the line 3 3, Fig. 1.

a is the reservoir for containing the solution, and *b* is the cylinder of the pump for 60 forcing the solution into the tubes or other receptacles to be filled.

c is a pipe or passage by means of which the reservoir *a* is placed in communication with the rear end of the pump-cylinder *b*. 65 Communication can be cut off between the reservoir *a* and the pump-cylinder *b* from the exterior by means of a cock *d*, fitted to the pipe *c*, and also by means of a small slide-valve *e*, arranged in the reservoir and adapted 70 to be operated by a rod *f*, which passes through the wall of the reservoir and is provided with an external knob *g*.

h is the piston, reciprocated by the piston-rod *i*, as hereinafter described, and provided 75 with a valve *j*, arranged to open so as to allow the solution to pass through the piston during its backward stroke.

k is the nozzle, upon which the tube *l* to be filled is placed, the said nozzle *k* being screwed 80 to a connection or neck *m* upon a sleeve *n*, adapted to slide between shoulders upon the front end of the pump-cylinder *b*, the interior of which is placed in communication with the nozzle *k* through a lateral hole *b'* in the said 85 cylinder *b* when the sleeve is placed in such a position that the connection *m* comes opposite the said hole *b'*. The sleeve *n* is also provided with a hole *n'*, which by partially turning or sliding the sleeve upon the end of 90 the cylinder *b* can be brought opposite a hole *b''* in the under side of the cylinder, so as to allow the solution to escape in a downward direction through the said holes *b''* and *n'*.

o is the valve for controlling the escape of 95 the solution from the pump-cylinder *b*, the said valve *o* being arranged to slide in the front end of the pump-cylinder *b* and being operated as hereinafter described.

The arrangement which I provide for recip- 100

roating the piston h and for controlling the flow and supply of the solution to and from the pump-cylinder b consists of a handle or lever p , pivoted at a point intermediate between its two ends to the piston-rod i and at the end opposite the handle to one end of a double link q , the other end of which is pivoted to one end of a double link r . The other end of this link r is pivoted to one end of a double link s , the other end of which is pivoted to a forked link t , hinged to the front end of the pump-cylinder b . The link s is pivoted at a point intermediate between its two ends to the rod u of the valve o , which rod passes through the front end of the pump-cylinder b . The connected ends of the two links q and r are pivotally connected by a link v to the reservoir a of the apparatus, and a link w is pivoted to the said link v at one end. This link w is provided at its other end with a slot w' , which engages with a pin x on a bracket y , secured to the reservoir a , the object of the link being to limit the movement of the series of links by the movement allowed to the said link by the slot w' .

z is a spring connecting the two links s and r for the purpose of normally holding the valve in such position that the outlets from the pump-cylinder b are closed—that is to say, in the position shown in Fig. 2.

The reservoir a is provided with a device for mixing the solution therein before its passage to the pump-cylinder b . This mixer, which is of ordinary construction, consists of a number of arms a' , mounted upon a vertical spindle c' , suitably supported in the reservoir and adapted to be rotated by bevel-gear d' , operated by an external handle e' . f' are arms arranged in the reservoir between the arms a' of the mixer, so as to insure the proper working of the solution.

The operation of the apparatus is as follows: Assuming the solution to have been well mixed in the reservoir a , the valves e and d are opened and the handle p is pressed toward the reservoir, so as to push the piston h forward and thereby draw in a supply of solution from the reservoir. When the piston has reached the limit of its stroke in the forward direction, the handle is pulled outward, so as to draw back the piston and allow the solution which has filled the cylinder b behind the piston to pass through the valve j in the piston and fill the cylinder in front of the latter. When the limit of the backward stroke of the piston has been reached, the handle p is again pressed toward the reservoir a . The valve o being, as above described, held closed by the spring z , the solution which now

fills the cylinder b offers resistance to the forward motion of the piston. The pressure upon the handle p therefore causes the said lever to turn upon the piston-rod i , so as to move the links q , r , s , and t upon their pivots and push the valve o farther into the pump-cylinder b in such a manner as to cause it to uncover the openings b' and b^2 . The solution is therefore now free to escape either through the nozzle k into the tube l or through the holes b^2 and n' , so that the piston h can move forward and force the solution out of the cylinder. When the tube has been filled, the operator releases the handle and the spring z immediately closes the valve o , thus enabling the tube l to be removed from the nozzle k without the loss of any solution.

It will be obvious that the reservoir a can communicate with the front end of the pump-cylinder b instead of with the rear end, as in the construction above described and illustrated herewith. In this case the piston h draws in a charge of solution during its backward stroke instead of during its forward stroke.

Having now particularly described and ascertained the nature of my said invention and in what manner the same is to be performed, I declare that what I claim is—

1. The combination with a cylinder provided with a discharge-opening at one end, of a sleeve surrounding the cylinder and inclosing said opening, said sleeve having a discharge-passage adapted to register with said opening, and a tube-holding nozzle communicating with said passage, of a valve in said cylinder normally closing said discharge-aperture, a spring holding said valve in closed position, a piston in said cylinder and means for operating said piston, connected with said valve, for opening the same when the piston is advanced, substantially as described.

2. The combination with a cylinder having a discharge-aperture adjacent to one end, a sleeve surrounding said piston and said aperture, said sleeve being provided with an opening and with a nozzle each adapted to register with an aperture in the cylinder, a valve normally closing the discharge-aperture of the cylinder, a spring holding said valve in closed position, a piston in said cylinder and means for operating said piston, connected with said valve for opening the same when the piston is moved forward, substantially as described.

WILLIAM CHARLES BRETT.
